UNITED STATES PATENT OFFICE.

IHNA T. FRARY, OF HUDSON, OHIO, ASSIGNOR TO THE HOCKING GLASS COMPANY, OF LANCASTER, OHIO, A CORPORATION OF OHIO.

DESIGN FOR A LIGHTING-FIXTURE.

48,544.

Specification for Design.

Patented Feb. 15, 1916.

Application filed September 8, 1915. Serial No. 49,642. Term of patent 7 years.

To all whom it may concern:

Be it known that I, IHNA T. FRARY, a citizen of the United States, and a resident of Hudson, in the county of Summit and State of Ohio, have invented a certain new, original, and ornamental Improvement in Designs for Lighting-Fixtures, of which the following is a specification, reference being had to the accompanying drawing, forming part thereof, in which—

Figure 1 is a side elevation of the lighting fixture showing my new design; Fig. 2

is a face view of the same; and Fig. 3 is a face view of the bracket employed.

I claim:—

The ornamental design for a lighting fixture, as shown.

In testimony whereof, I, the said IHNA T. FRARY, have hereunto set my hand.

IHNA T. FRARY.
